UNITED STATES PATENT OFFICE

JESSE G. KING, OF DAYTON, OHIO, ASSIGNOR, BY MESNE ASSIGNMENTS, TO FRIGIDAIRE CORPORATION, A CORPORATION OF DELAWARE

REFRIGERATING APPARATUS

Application filed November 30, 1927. Serial No. 236,719.

This invention relates to improvements in refrigerating apparatus and has specific reference to the refrigerating means used in connection with the production of cold in mechanically refrigerated cabinets.

It is an object of the invention to provide an improved refrigerating means adapted for use especially in large display counter refrigerators or the like, which will maintain a substantially uniform temperature throughout the length of the cabinet. The invention contemplates providing a refrigerating means which is arranged and constructed to compensate for heat leakage, which is greater in some parts of the cabinet than others, and by such compensation tends to maintain an even temperature throughout the cabinet.

In the present invention a hold-over, such as a brine solution, is utilized in connection with the refrigerating means and another object of the invention is to provide for the ready transfer of heat units from the hold-over to the refrigerating means.

Further objects and advantages of the present invention will be apparent from the following description, reference being had to the accompanying drawings, wherein a preferred form of the present invention is clearly shown.

In the drawings:

Fig. 1 shows a top view of the improved refrigerating element of the invention in broken separated form;

Fig. 2 represents a side view thereof;

Fig. 3 is an end view of the element;

Fig. 4 illustrates a display counter refrigerator equipped with the improved refrigerating element;

Fig. 5 is a side view in section of the display counter;

Fig. 6 is a side view of the refrigerating element within a hold-over tank, the tank being shown in section; and

Fig. 7 shows a plurality of refrigerating elements disposed with a hold-over tank.

Referring in detail to the drawings, the refrigerating element comprises a header 10 shown complete in Fig. 6 but in broken separated arrangement in Figs. 1 and 2 which serves as a container for refrigerating me-

dium which may, for example, be liquid sulphur dioxide. This header is used to distribute the refrigerant to pipes or ducts hereinafter described. The refrigerating medium is led into the header by a pipe 11 and is conducted away therefrom above the liquid level in the header by a pipe 12. A suitable float valve 13 (Fig. 6) is used to control the flow of refrigerant to the header and adapted to maintain a constant level of liquid in the header.

A series of heat transfer devices herein shown as refrigerant circulating ducts or pipes which are formed of a plurality of loops of pipe are connected to the header in parallel circuit relation, as shown in the drawings, Figs. 1 and 2. These loops extend outwardly into a hold-over tank herein-after described and serve to cool the same. Four loops are shown and indicated as loops 15, 16, 17 and 18. Each loop, respectively, is provided with an outwardly extending portion, 15^a, 16^a, 17^a and 18^a, which incline downwardly (see Fig. 6) and each loop includes, respectively, portions 15^b, 16^b, 17^b and 18^b, which are inclined at substantially the same angle as the first portions of the respective loops but are located in a lower plane and offset laterally from the first portion. These inclined portions of each loop are connected, respectively, by loop portions 15^c, 16^c, 17^c and 18^c. The upper ends of the inclined portions are connected to the end of the header 10 and below the liquid level in the header (see Fig. 6). By inclining the loops as shown the possibility of obtaining a trap in the loop portion when the header is accidentally placed in a position tilting upwardly toward the right end of element (as viewed in Fig. 6) is minimized, also such inclining provides for a more natural and therefore a more ready flow of the refrigerant.

The loops are arranged to be placed in a brine tank 20 while, as a preferred embodiment, the header is arranged exteriorly of the tank. The end of the tank adjacent the header is open and is secured in a suitable manner on a flange 21 of the brine tank. In case it is desirable to utilize two refrigerating

elements, both ends of the tank are open, as shown in Fig. 7. A fin 22 is suitably secured, as by soldering, along inclined portions of each duct and since these fins are immersed in the brine within the tank, they provide for the ready transfer of heat units from the brine to the loops and extend vertically whereby the circulating brine passes over same, which arrangement materially increases such heat transfer.

10 It is apparent from the foregoing that refrigerating means has been provided for cooling a relatively long, narrow chamber such as a display counter, shown in Figs. 4 and 5. This display counter includes an heat insulated chamber 23 provided with a glass front 24 and glass doors 25. The brine tank is installed adjacent but spaced from the back wall and bottom wall for the circulation of air thereabout. The brine tank is preferably rectangular in contour and the top side provides a shelf for foods which can rest on the cold tank and thereby be maintained relatively cold compared with foodstuffs placed more remote from the tank.

25 Since heat leakage into the box, along the lengths of the refrigerating means, is greater adjacent the ends of the cabinet, I compensate for this heat leakage by disposing the colder part of the refrigerating means, namely, the header, adjacent the ends of the cabinet and in this manner maintain a substantially uniform temperature throughout the length of the cabinet.

35 While the form of embodiment of the invention as herein disclosed, constitutes a preferred form, it is to be understood that other forms might be adopted, all coming within the scope of the claims which follow.

40 What is claimed is as follows:

1. Refrigerating means for mechanically refrigerated cabinets comprising a brine tank having an opening in an end wall, a header disposed externally to said brine tank and attached to an end wall thereof and providing a cover for said opening, refrigerant circulating ducts within said brine tank and connected to said header.

45 2. Refrigerating means for mechanically refrigerated cabinets comprising a brine tank having an opening in an end wall, a header disposed externally to said brine tank and attached to an end wall thereof and providing a cover for said opening, refrigerant circulating ducts within said brine tank and connected to said header, said ducts being provided with fins attached in good thermal contact with said ducts.

50 3. In combination, an elongated cabinet for stores or the like having an elongated storage compartment, a brine tank extending longitudinally of the storage compartment, refrigerating means including headers disposed external of the opposite ends of the brine tank and duct means connected with the

headers and extending within the brine tank.

4. Refrigerating means for mechanically refrigerated cabinets comprising a brine tank having an opening in an end wall, a cooling unit including a reservoir adapted to contain liquid refrigerant, refrigerant conveying duct means connected to one end of the reservoir and extending through said opening, and means for attaching the reservoir to said brine tank and for providing a cover for said opening.

5. Refrigerating means for mechanically refrigerated cabinets comprising a brine tank having an opening in an end wall, a cooling unit including a reservoir adapted to contain liquid refrigerant, refrigerant conveying duct means connected to one end of the reservoir and extending through said opening, and means on said end of the reservoir for attaching the reservoir to said brine tank and for providing a cover for said opening.

6. Refrigerating means for mechanically refrigerated cabinets comprising an elongated brine tank having an opening in an end wall, a cooling unit including a reservoir adapted to contain a quantity of liquid refrigerant, refrigerant conveying duct means connected with the reservoir and extending longitudinally of the brine tank, said duct means extending through the opening in the end wall and said reservoir being connected exteriorly of the brine tank and to said end wall.

7. Refrigerating means for mechanically refrigerated cabinets comprising an elongated brine tank having an opening in an end wall, a cooling unit including an elongated reservoir adapted to contain a quantity of liquid refrigerant, refrigerant conveying duct means connected with an end of the reservoir and extending longitudinally thereof and longitudinally of the brine tank, said duct means extending through the opening in the end wall and said reservoir having the said end thereof connected to said open end wall of the tank.

In testimony whereof I hereto affix my signature.

JESSE G. KING.
